UNITED STATES PATENT OFFICE.

THEODORE L. SMITH, OF DETROIT, MICHIGAN.

RAT-TRAP.

No. 895,050.

Specification of Letters Patent.

Patented Aug. 4, 1908.

Application filed November 16, 1907. Serial No. 402,428.

To all whom it may concern:

Be it known that I, THEODORE L. SMITH, a citizen of the United States, and a resident of Detroit, in the county of Wayne and State 5 of Michigan, have invented a new and Improved Rat-Trap, of which the following is a specification.

This improvement relates broadly to fastening devices between longitudinal and 10 transverse members of metal webs, and the object of this invention is to provide a construction whereby flat longitudinal members and round transverse members may be secured together.

15 My invention, a fastener for metal webs to form tubes, comprising flat longitudinal members and transverse members of any form, consists of staggered fingers formed by diagonally slitting the alternate edges of the 20 flat members at different sections and turning them up, the fingers being turned down over the transverse members after they are positioned to hold them in place.

My invention is particularly adapted to 25 rat-traps for fastening together the longitudinal and circumferential members, and in the accompanying drawings, Figure 1 is a general view of a trap. Fig. 2 is a view of a 30 section of a longitudinal member showing the fingers turned up. Fig. 3 is a view of a similar section with transverse members held in place by the turned down fingers.

Similar reference characters refer to like 35 parts throughout the several views.

The form of trap shown in Fig. 1 has been 40 in general use for some time, the longitudinal and transverse members being of round wire and secured together by means of a light wire passing around both members at their 45 points of contact. The union was far from positive, so the transverse wires were often separated by imprisoned rats. The thin fastening wires quickly rusted off and the trap became useless. The cost of "lacing" 45 in the fastening wires by hand is very great.

The longitudinal members 1 shown in the drawings are strips of metal about one fourth of an inch wide and about fifteen one-thousandths of an inch thick. The fingers 2 50 measure about one-fourth inch long, and are about one tenth inch wide at the base. These dimensions are such as I have found to give satisfaction, but may be varied from as desired by having the edges of the longitudinal members slitted alternately or stag-

gered, that is, not directly opposite, it is possible to use a strip of metal of much narrower width and be stronger and stiffer than when oppositely slotted. Each ring is held by each rib so that one finger is only necessary and required to be turned down, thus avoiding extra operations and cost of manipulation.

The body of the trap is formed on a mandrel having the desired form. The longitudinal members are positioned and their ends hooked onto the first ring of circumferential wire 3 at 4. The mandrel then revolves, winding the wire 3 in place, the fingers 2 being bent down to hold the wraps of wire in position. The opposite ends 6 of the strips are also bent over to grip the final wrap of wire. The door 7 is then put in, the trap-door holding screen 8 is inserted; and the conical end 9 is secured in position, completing the trap. The auxiliary parts are all constructed in the same manner as the shell of the trap, of flat and round members, the flat members having the fingers 2 to hold the round members in position. While this 70 method of fastening is particularly adapted to rat-traps, it may be employed to form any other wire fabric.

Having now explained my improvements, what I claim as my invention and desire to 85 secure by Letters Patent is:—

1. A rat trap comprising a series of flat longitudinal metal members having their opposite edges slitted alternately or staggered and diagonally to form retaining fingers, and circumferential wire members extending around the flat members and held in position by said fingers, the ends of the flat members being bent to hook around the circumferential members at the ends of the trap. 90

2. A rat trap comprising a series of spaced flat longitudinal members having their opposite edges slitted alternately or staggered and diagonally to form retaining fingers, and a circumferential member wound spirally around the longitudinal members and held in position by said fingers. 100

In testimony whereof, I have signed this specification in the presence of two subscribing witnesses.

THEODORE L. SMITH.
